pany, Terre Haute, Ind., a corporation of Indi-
ana

Application March 13, 1939, Serial No. 261,572

6 Claims. (Cl. 229—52)

Our invention relates to containers, and especially to containers particularly adapted for carrying bottles. It is the primary object of our invention to produce a low-priced container which will provide adequate protection for its contents and which will be sturdy and durable in use.

In carrying out our invention, we form the container of corrugated paper or some equivalent material and reinforce it with a wire frame. The wire frame has a plane bottom, upon which the weight of the box-contents is carried, a pair of upstanding yokes at opposite ends, and a tie between the upper ends of such yokes. The container is built to receive the reinforcing frame and has in its end walls finger openings left when tongues formed from the material of the end walls of the container are folded inwardly around transversely extending portions of the yoke on the reinforcing frame.

The accompanying drawing illustrates our invention: Fig. 1 is a perspective view of the complete container; Fig. 2 is a perspective view of the reinforcing frame; Fig. 3 is a perspective view showing the reinforcing frame provided with a set of dividing partitions; and Fig. 4 is a fragmental vertical section through one end wall of the complete container.

As will be clear from the drawing, the container of corrugated paper or some similar material is formed with a bottom, side walls 10, and end walls 11. The reinforcing frame illustrated in Fig. 2 fits snugly within the container and is conveniently formed of wire. Desirably, the bottom of the reinforcing frame is formed with a continuous border 15 to which there are secured a series of transversely extending members 16, desirably also of wire and having their ends secured to the border, as by welding. At each end of the bottom there is secured thereto, as by welding, an upstanding yoke 17 conveniently in the form of a wire bent to U-shape.

A short distance below the top of each yoke 17 we provide a transverse strut 18 extending between and secured to the parallel legs of the yoke; and between the two struts 18 we provide a tie rod 19. In addition, we may provide the reinforcing frame with an auxiliary border member 20 disposed intermediate the height of the yokes 17, secured thereto, and conforming generally to the shape of the bottom of the reinforcing frame.

The end walls of the container are provided with extension flaps 22, which are foldable inwardly of the container over the transverse leg 17 at the top of each U-shaped yoke 17. In addition, each of the end walls 11 is provided with a

finger-opening 23 formed by cutting from the material of the end wall a tongue 24 which is folded inwardly around the associated strut 18, as is clear from Fig. 4, such tongue being slotted centrally to clear the tie-rod 19. The inwardly folded extension 22 and tongue 24 are secured to the end wall 11 of the box, as by staples 25.

Desirably, each of the flaps 22 is provided at its ends with extensions 26 which extend downwardly along the inner face of the associated end-wall 11 of the box on opposite sides of the finger openings 23 therein, such extensions being secured to the end wall, as by staples. In addition, each of the flaps 22 is provided centrally with a narrow notch 27 which extends downwardly nearly to the fold-line separating the end wall 11 from the flap 22 and which has a purpose to be made apparent hereinafter.

The side walls 10 of the container are provided with extension flaps 30 foldable inwardly over the contents of the box. Extending across each of the flaps 30 near the outer edge thereof is a score-line 31 about which the extreme outer edge portion 32 of the flap may be folded to extend downwardly and inwardly of the box when the flaps 30 are closed. At its ends, each edge portion 32 is notched, as indicated at 33, to leave short tongues 34 which, when the flaps 30 are closed, enter the notches 27 in the in-folded flaps 22 and act yieldingly to prevent accidental raising of the flap 30. Each of the flaps 30 may be provided with a finger hole 36 for the purpose of raising it when it is desired to open the box.

When the box is used as a container for bottles, it may be divided into a multiplicity of compartments by a set of longitudinal and transverse partition members 37, as indicated in Fig. 3.

The container above described may be simply and economically manufactured. Because the yokes 17 extend for the full height of the container, the container is reinforced against vertical crushing forces, and the bottom frame 15 and auxiliary border frame 20 reinforce it against horizontal crushing forces. When the box is lifted, the lifting strain is applied directly to the cross-struts 18 of the yokes 17 and transmitted through the yokes to the frame-bottom 15—16, and thus none of the lifting strain is imposed upon the container itself. If the container is lifted by one hand so that it occupies a generally vertical position, the lifting effort will be transmitted through the tie rod 19 to the yoke 17 at the lower end of the container and thence to the auxiliary border frame 20, and the container it-

self sustains no appreciable portion of the lifting effort.

We claim as our invention:

- 5 1. In combination, a container having a bottom, side walls, and end walls, and a reinforcing frame within said container, said frame having a bottom portion conforming in size and shape to the container, a yoke secured to each end of said reinforcing frame and extending upwardly therefrom along the inner surface of the adjacent end wall for substantially the entire height thereof, said yoke having a cross-piece intermediate its height, each of said end walls being provided with a cut-out tongue folded inwardly and upwardly around the cross-piece of the associated yoke and secured to the body of the end wall.
- 10 2. In combination, a container having a bottom, side walls, and end walls, and a reinforcing frame within said container, said frame having a bottom portion conforming in size and shape to the container, a yoke secured to each end of said reinforcing frame and extending upwardly therefrom along the inner surface of the adjacent end wall for substantially the entire height thereof, said yoke having a cross-piece intermediate its height, each of said end walls being provided
- 15 3. In combination, a container having a bottom, side walls, and end walls, and a reinforcing frame within said container, said frame having a bottom portion conforming in size and shape to the container, a yoke secured to each end of said reinforcing frame and extending upwardly therefrom along the inner surface of the adjacent end wall, said yoke having a cross-piece, each of said end walls being provided with a cut-out tongue folded inwardly and upwardly around the cross-piece of the associated yoke and secured to the body of the end wall above said cross piece.
- 20 4. The invention set forth in claim 3 with the addition of a tie-rod extending between and secured to the cross-pieces on said yokes.
- 25 5. The invention set forth in claim 3 with the addition of an auxiliary border member, said member being secured to said yokes and extending around the interior of the box in a plane above the frame-bottom.
- 30 6. The invention set forth in claim 3 with the addition that the bottom portion of said frame and said yokes are formed of wire and welded together.

with a cut-out tongue folded inwardly and upwardly around the cross-piece of the associated yoke and secured to the body of the end wall above said cross piece.

3. In combination, a container having a bottom, side walls, and end walls, and a reinforcing frame within said container, said frame having a bottom portion conforming in size and shape to the container, a yoke secured to each end of said reinforcing frame and extending upwardly therefrom along the inner surface of the adjacent end wall, said yoke having a cross-piece, each of said end walls being provided with a cut-out tongue folded inwardly and upwardly around the cross-piece of the associated yoke and secured to the body of the end wall above said cross piece.

4. The invention set forth in claim 3 with the addition of a tie-rod extending between and secured to the cross-pieces on said yokes.

5. The invention set forth in claim 3 with the addition of an auxiliary border member, said member being secured to said yokes and extending around the interior of the box in a plane above the frame-bottom.

6. The invention set forth in claim 3 with the addition that the bottom portion of said frame and said yokes are formed of wire and welded together.

JOSEPH A. MOOTER.
